UNITED STATES PATENT OFFICE.

JAMES H. MANN, JR., OF MONTEAGLE, TENNESSEE, ASSIGNOR TO SOUTHWESTERN SALES CORPORATION, OF NEW YORK, N. Y., A CORPORATION OF DELAWARE.

MOUNTABLE AND DEMOUNTABLE CASING FOR COIN-CONTROLLED DEVICES.

Application filed February 27, 1924. Serial No. 695,483.

This invention relates to casings for coin control vending machines and has especial reference to those in which the side walls of the casing are movable and are locked in 5 place by a single keyed device.

In coin operated receptacles it is desirable that the casing when mounted on a support can not be removed without first unlocking the device. Moreover it is important 10 to limit the number of keys and locks required for a single unit when operating such devices in order to economize in servicing. In the casing of the present invention a lock must be opened to replenish the device.

15 In the interest of economy of time in the collection of coins deposited therein the lock carrying cover of the coin chamber is first removed by the operation of a slide or control which preferably is not attached or operated by the lock carrying cover. Should an unsuccessful attempt be made to pry open the lock carrying side, the slide or control is unaffected thereby, so that operation can still 20 normally continue because jamming of the slide cannot occur by prying open the cover. When the coin chamber is emptied the slide or control can be replaced to normal position. Means are provided for dismounting 25 my casing from its support and mounting plate by disengaging a bolt or the like to permit the casing to slide away from the back or mounting plate. This arrangement permits the interchange of parts and contents, by merely mounting the new casing 30 upon the back plate on the wall, the attaching screws of the back plate only being visible when the main casing is removed.

35 It is preferable that the lock carrying cover be entirely detachable from the casing and therefore hinges are not desirable.

Figure 1 is a perspective view of my invention;

Figure 2 is a rear view of the same;

40 Figure 3 is a front elevation of the mounting plate of my casing;

Figure 4 is a rear view of Figure 3;

Figures 5 and 6 are plan views of the cover

of my casing in locked and unlocked positions, respectively;

50 Figures 7 and 8 are edge views of Figures 5 and 6, respectively;

Figure 9 is a perspective view of the locking bolt of the case cover;

55 Figure 10 is a top plan view of my casing with the cover removed;

Figure 11 is a back view of the casing with the back plate removed; and

Figure 12 is a detail perspective of the 60 sliding bar of my device.

A casing 1 is provided with a side opening 2 and a larger back opening 3. A cover or cap 4 is mounted for the top while the opening 2 is closed by a sliding bar 5 and the back plate 6 closes the back opening. The back plate 6 is provided with perforations 7 for attachment to a support to which the casing is demountably locked. Ordinarily the mounting plate 6 is left in position when the casing 1 is detached therefrom, whether for 65 filling the casing and operating the bar 5, or for substitution of another case thereon. The bar 5, as shown, carries an offset leaf spring A which coacts with a coin receptacle more fully described in my copending application for patent, Serial No. 22,276, filed April 11, 1925. The upper end of the bar is provided with an offset portion B, and a shutter C at the lower end for closing the 70 lower opening. 75

80 It is therefore important that the casing be easily detached from the mounting plate and yet when assembled on its support the plate shall cooperate with the locking cover to resist the use of any prying up tool that 85 may be employed to forcibly open the cover.

The back of the casing is provided with a series of oppositely projecting depressed flanges 8 whereby the back plate 6 is flush with the back wall proper 9 of the casing, 90 when in assembled position. The lower end of the back plate is displaced to form a parallel lip 10 to lock in front of the lower edge 11 of the back casing structure. Said lip 10 is of sufficient length to still engage with the 95 edge 11 when the plate 6 is raised upwardly

into locked position with the parallel ears 12 passing through the slots 13 of the casing back. Thereafter to maintain the back plate as a properly positioned demountable unit for the casing a bolt 14 riding between guiding lugs 15, 15', lip 16 and lug 17 is enabled to pass between the top 18 of upper left hand flange 8 as viewed from the back of the casing, and the lug 17 integral with the back plate. 10 To aid in maintaining such relation an offset 19 on the bolt 14 fits over the top portion 18 of one of the flanges 8 and the ears 12 engage with the flanges 8 through the openings 13. The lip 16 of the back plate has a slot 20 within which slides a lug 21 of the bolt 14.

The bolt may be operated by the upturned portion of 22 which may be formed by bending up one end thereof. By moving the bolt backwardly the plate 6 can be pushed downwardly relatively to the casing and disengaged therefrom. The lip 16 and lug 17 maintain the lock cover in assembled position after the lock has been attached. Said arrangement of parts interconnects the cover 25 and the casing together with the back plate and produces a double protection against forcing an opening of the casing.

Referring to Figures 5 and 6 of the drawings, it will be seen that catches 23, 24 are 30 mounted on the cover for engagement respectively with the lip 25 and lug 17. To facilitate such assembly the top of the casing is bevelled at 26 to permit the parts coming together. Before the cover 4 may be attached 35 to the casing, it is necessary to throw the bolt 14 to its locked position in respect to the casing and to position the back or mounting properly with respect thereto. Thus for closing the casing the upturned portion 22 must 40 be positioned under the back plate lip 16 in which case the back catch 24 is then enabled to ride under the lip 16.

The final locking bolt action for the cover 45 does not take place directly by means of the snap bolt 28 of a spring lock 29, but by virtue of an intermediate bolt plate 30 having ends 31 and 32 which are to engage with the lugs 33 and 17 respectively on the casing and the back 50 mounting plate. Guide blocks 34 and 35 are integrally arranged upon the cover plate which together with bolt plate projections 36 and 37 cooperate to maintain the locking bolt plate in place by virtue of an additional guide 55 block 38 arranged near the snap bolt 28 and a lug X on the plate 30 working in a slot 39 of the cover plate. In this manner the locking bolt plate is firmly held in position.

On the outside of the cover through the 60 slot 39 extends a lock snapping pin 40 made integral with the bolt plate 30. When the cover is positioned on the casing the bolt plate moves under the lugs 33 and 17 by shifting the pin 40 in the slot 39 from the outside of the cover and when in place the cover will 65 be secured provided the bolt plate is moved

sufficiently out of the way of the snap bolt 28 that a lug 41 integral with the plate and keeping the spring snap bolt 28 in depressed condition releases the same. With such release the lug 41 is locked in position by being held in place by the outward movement of the depressed snap bolt 28. To facilitate release however a spring 42 is employed tending to bring the bolt plate into unlocked position. One end of the spring therefore is attached 70 to the back end 28' of the snap bolt 28 and the other end to the bolt plate. When the spring lock 29 is actuated in the usual manner from the outside the snap bolt 28 is again depressed allowing the bolt plate lug 41 to ride over it and maintain such locked position of the locking spring bolt until released by moving the pin 40 in the slot 39.

In the disassembly of the parts of the casing and cover, a key is employed to retract 85 the snap bolt 28 to the position shown in Figure 6. The spring 42 then draws the bolt plate 30 into unlocked position. The cover may then be removed, and the interlocked 90 parts of the interior of the casing disassembled as hereinbefore described.

Having described the nature of my invention what I claim is:

1. In combination with a casing having a locking lug thereon, a cover plate comprising 95 a bolt plate movably arranged thereon adapted for engagement with said locking lug, and a lock on said cover having its locking bolt when in locked position in the path of the normal line of action of said movable bolt plate, 100 to lock the latter in position, and when said locking bolt is withdrawn leaving said bolt plate free to move in its normal path.

2. In combination with a casing, a locking 105 cover for said casing, said locking cover comprising a locking means and a movable bolt plate thereon, means on said bolt plate for locking said locking means in unlocked position, said locking means comprising means for locking said bolt plate in locked position. 110

3. In combination with a casing, a cover 115 for said casing, a key actuated locking bolt and a spring actuated locking plate carried on said cover, said locking bolt normally locking said spring actuated plate in locked position, and said spring actuated plate automatically holding said locking bolt in unlocked position.

4. In combination with a casing, a cover 120 for said casing having a slot therein, a key-actuated bolt and a spring actuated locking plate carried on the cover, a projection on said plate slidable in said slot, said key-actuated bolt locking said spring actuated plate in locking position and said spring actuated plate holding said bolt in unlocked position. 125

5. In combination with a casing, a slotted 130 cover therefor, a locking means on said cover comprising a sliding plate and a bolt controllable from the outside of the cover, and means

on the sliding plate for locking said bolt in unlocked position.

6. In combination with a casing having side, top and back openings therein, a wall plate for closing the back opening, a slidable bar for closing the side opening, a lockable cover for closing the top opening, said cover

when in closed and locked position locking said back and side closures in closed position, substantially as described.

In testimony whereof I have hereunto set my hand.

JAMES H. MANN, JR.
